UNITED STATES PATENT OFFICE.

PIERCE J. MURPHY, OF TECUMSEH, NEBRASKA.

AUTOMATIC SAFETY SIGNAL DEVICE.

1,402,640.

Specification of Letters Patent. Patented Jan. 3, 1922.

Application filed July 29, 1921. Serial No. 488,429.

To all whom it may concern:

Be it known that I, PIERCE J. MURPHY, a citizen of the United States, residing at Tecumseh, in the county of Johnson and 5 State of Nebraska, have invented new and useful Improvements in Automatic Safety Signal Devices, of which the following is a specification.

This invention relates to signaling devices 10 for use on railroads and has for its object the provision of a signal primarily designed for use at corners whereby to warn persons desiring to cross the tracks of the approach of a train, the device being so constructed that 15 a semaphore signal will be automatically thrown to the danger indicating position when the train reaches a certain predetermined point in the track.

An important object is the provision of a 20 device of this character which may also be used as a block signal as well as a crossing signal, the construction and operation being the same in either event, and the arrangement being such that the signal will not be 25 affected by a train passing from a crossing or block as a specially constructed trip device is provided which is capable of actuation in only one direction.

A further object is the provision of a 30 signal device which is positively thrown to danger indicating position upon approach of a train and which will automatically return to normal position more or less slowly, the rate of return being controlled by a compression cylinder having an adjustable valve 35 therein.

An additional object is the provision of a 40 device of this character which will be comparatively simple and inexpensive in construction and installation, highly efficient in use, durable in service, and a general improvement in the art.

With the above and other objects and advantages in view, the invention consists in 45 the details of construction to be hereinafter more fully described and claimed and illustrated in the accompanying drawings in which

Figure 1 is a somewhat diagrammatic view 50 of a trackway and crossing showing a signal device associated therewith,

Figure 2 is an enlarged plan view of the track mechanism,

Figure 3 is a side elevation thereof.

55 Figure 4 is a cross sectional view through

the track showing an end view of the track mechanism,

Figure 5 is an elevation of the signal device in normal or inoperative position,

Figure 6 is a similar view showing the 60 signal arm as moved to danger position,

Figure 7 is a vertical sectional view through the pump cylinder,

Figure 8 is a detail cross sectional view of 65 a portion of the track showing the trip member.

Referring more particularly to the drawings, the letter A designates a trackway and B designates a crossing, though it is to be distinctly understood that the signal device 70 to be hereinafter described may be used at the beginning and end of a block instead of at a crossing though only the latter will be described as the operation in the event of the former use is readily understandable. In 75 carrying out my invention as applied to a crossing, I provide a suitable upright support 10 mounted at the crossing and near the track. Pivoted upon this support is an arm 10^a upon which is pivoted, as shown at 11, a 80 semaphore arm 12 of suitable construction which is movable to be disposed in a downwardly extending position indicating safety or to extend in a horizontal position indicating danger. Also secured upon this support 85 10 is a vertical cylinder 13 within which operates a piston 14 carried by a piston rod 15 operating through a suitable guide 16 on the support 10. The cylinder 13 may contain air, oil or other liquid, and the piston 90 14 is valved whereby the fluid at either side thereof may pass to the other side, the valve being so constructed that it is in the nature of a check valve which will permit the piston to move downwardly freely but retard its 95 upward movement, the retardation depending upon adjustment of a regulating screw. This valve is designated by the numeral 17 and the screw by the numeral 18. The semaphore arm 12 has a pivoted connection 19 100 with the piston rod 15 so that the piston of the semaphore arm will be governed by movement of the piston and the piston rod. The numeral 20 designates a spring which normally holds the piston rod and piston upwardly with the semaphore arm in inoperative or normal position.

Located on the track beside one of the rails thereof, at any desired point in advance of the crossing, is a trip 21 carried 110

by a shaft 22 journaled in bearings carried by plates 23 secured upon the ties. The shaft 22 carries a large gear 24 which meshes with a small gear 25 mounted upon one end 5 of a drum 26 which is journaled within bearings 27 mounted on a post or block 28 embedded at the side of the track. A cable, chain or wire 29 is secured at one end to the drum 26 and is wrapped thereabout, this 10 flexible member being then lead over a plurality of guide pulleys 30 suitably mounted on posts 31 located at the side of the trackway, the flexible member having its other end extending to the signal device and connected with the short end of the arm 12.

The trip 21 is not rigidly secured upon the shaft 22 but may move idly in one direction upon the shaft, movement in the other direction effecting rotation of the shaft. 20 This might be accomplished in a great variety of ways though I have shown the trip as rotatably mounted on the shaft 22 and provided with a slot 32 through which projects a pin 33 extending laterally from 25 the shaft 22. The numeral 34 designates a spring which has one end connected with the end of the pin 33 and which has its other end connected with the adjacent side of the trip, the purpose of this spring being to 30 hold the trip normally against the pin 33.

In the operation of the device it will be seen that when a train approaches a crossing the flanges of the wheel at one side of the train will strike against the trip 21 and 35 swing it downwardly whereupon the engagement of the trip with the pin 33 will cause partial rotation of the shaft 22 and consequently the gear 24. The movement of the gear 24 causes rotation of the pinion 40 25 and drum 26 and as the drum is rotated the flexible member 29 will be wound thereonto and this will result in pulling upon the flexible member. As the flexible member is pulled it is apparent that the signal arm 45 12 will be swung upwardly into horizontal or danger indicating position, as shown. When the train has passed by and the last wheel has gone beyond the trip, the parts will return to normal position under the influence of the spring 20 associated with the 50 piston 15 and the spring 34 associated with the trip. The return of the signal arm 12 to normal position is not rapid in order to avoid such return until the train has had 55 an opportunity to reach and pass the crossing. The degree of retardation of the movement is governed entirely by the valve and mechanism of the pump piston operating within the fluid filled cylinder. While only 60 one signal device and trip mechanism is shown, it is to be understood that two trip devices would be used at a crossing in the event of a single track upon which trains run in both directions, it being noted that 65 the trip construction is such that it will

operate to move the signal only when engaged by a train approaching the crossing, passage of a train in the other direction causing the trip member merely to move idly upon the shaft 22. In the event of a 70 double track it is of course apparent that either one or two signal members may be employed and of course two trip members, one of the latter being associated with each track. In the event that the device is used 75 as a block signal, it is apparent that the signal proper would naturally be so mounted that the arm 12 would extend transversely with respect to the trackway instead of transversely with respect to the roadway 80 as in the event of a crossing.

From the foregoing description and a study of the drawings it will be apparent that I have thus provided a simply constructed and easily installed signaling device which will operate entirely automatically and which will efficiently perform all the functions for which it is intended, the device, owing to its simplicity, being capable of having long life and requiring 90 practically no attention.

While I have shown and described the preferred embodiment of my invention, it is of course to be understood that I reserve the right to make such changes in the form, 95 construction, and arrangement of parts as will not depart from the spirit of the invention or the scope of the subjoined claims.

Having thus described my invention, I 100 claim:

1. A signal device comprising a movable signal arm located at a point to be protected, in combination with a track mechanism comprising a shaft carrying a gear and mounted along the track at a point remote 105 from the signal, a trip on said shaft, a winding drum having operative connection with said gear, and a flexible member secured to and trained about the drum and connected with said signal arm.

2. A signal device comprising a movable signal arm located at a point to be protected, in combination with a track mechanism comprising a shaft carrying a gear and mounted along the track at a point remote from the signal, a trip on said shaft, a winding drum having operative connection with said gear, and a flexible member secured to and trained about the drum and connected with said signal member, the trip member being freely 115 rotatable upon the shaft in one direction and causing rotation of the shaft when moved in the other direction.

3. A signal device comprising a movable signal arm located at a point to be protected, in combination with a track mechanism comprising a shaft carrying a gear and mounted along the track at a point remote from the signal, a trip on said shaft, a winding drum having operative connection with said gear, 125

and a flexible member secured to and trained about the drum and connected with said signal member, said trip being rotatable upon the shaft in one direction and being 5 formed with an elongated slot, and a pin extending laterally from the shaft and extending through said slot whereupon upon movement of the trip in the other direction rotation of the shaft will be caused.

10 4. In an automatic signaling device, a track mechanism including a shaft, a drum associated with and driven by said shaft, a flexible member secured to and trained about the drum and adapted to exert a pull upon 15 the signal member upon a remote point, a trip on said shaft and rotatable thereon freely in one direction, the trip being formed with an elongated slot adjacent the shaft, a pin extending laterally from the shaft and 20 through said slot and engageable by the trip when the latter is moved in the other direction, and a spring connected with said pin and with the adjacent side of the trip.

5. In an automatic signaling device, a 25 support located beside a track at a danger point, a signal arm pivoted intermediate its ends upon said support, means connected with said arm whereby to move the same

into signal position, a closed cylinder secured upon said support in upright position, a 30 piston within said cylinder and carrying a piston rod slideable through the upper head of the cylinder, a movable connection between said piston and the signal arm, spring means normally urging the signal arm into 35 inoperative position, said cylinder containing a fluid for retarding movement of the piston.

6. In an automatic signaling device, a support located beside a track at a danger point, 40 a signal arm pivoted intermediate its ends upon said support, means connected with said arm whereby to move the same into signaling position, a closed cylinder secured upon said support in upright position, a 45 piston within said cylinder and carrying a piston rod slideable through the upper head of the cylinder, a movable connection urging the signal arm into inoperative position, said cylinder containing a fluid for retarding movement of the piston, 50 said piston being provided with a check valve opening freely in one direction and practically seating in the opposite direction.

In testimony whereof I affix my signature. 55
PIERCE J. MURPHY.
